HUMIDOSTAT

Malcolm E. Henning, Des Moines, Iowa, assignor
to Penn Electric Switch Co., Des Moines, Iowa,
a corporation of Iowa

Application January 23, 1933, Serial No. 653,094

12 Claims. (Cl. 297—1)

An object of my present invention is to provide a hygroscopic control switch of simplified construction having an easily and inexpensively manufactured humidity responsive control member.

A further object is to provide a humidity responsive control member which is rugged in construction, yet very sensitive to humidity changes, the elements of the member being so formed and associated that there is an entire elimination of stresses and strains present in the usual type of humidity responsive member.

More particularly, it is my object to provide a humidity responsive member consisting of a corrugated resilient element and an element mounted alongside thereof with the ends of the elements secured together, the second mentioned element being responsive to humidity conditions for imparting swinging movement to both elements and thus providing a control member which can be utilized for opening and closing switch contacts or performing other controlling operations.

Still a further object is to arrange the control member in the form of a spiral so that considerable length without utilizing prohibitive space can be secured.

Another object is to provide means for adjusting the range of the humidity responsive member. With these and other objects in view my invention consists in the construction, arrangement and combination of the various parts of my device, whereby the objects contemplated are attained, as hereinafter more fully set forth, pointed out in my claims, and illustrated in the accompanying drawing, in which:

Figure 1 is a front elevation of a hygroscopic control switch embodying my invention showing the cover therefor removed.

Figure 2 is a side elevation of the same showing the cover in section.

Figure 3 is a diagrammatic view of the hygroscopic control member showing it in the dry position.

Figure 4 is a similar diagrammatic view showing it in the humid position.

Figure 5 is a diagrammatic view showing a hygroscopic control member which is not of spiral formation and illustrates the action of the member under exceptionally dry atmospheric conditions.

Figure 6 is a similar diagrammatic view showing different dimensions used for the parts and illustrating an exceptionally humid atmospheric condition; and

Figure 7 is an enlarged view of a connection used in the structure.

On the accompanying drawing, I have used the reference numeral 10 to indicate a base. The base 10 is provided with openings 12 and 14 through which screws may extend for securing the base to a wall or other surface.

A post 16 extends from the base 10 and has pivoted thereon, an arm 18. The arm 18 is adjustable by means of an arm 20 pivoted at 22 and having a pair of spaced sides 24 engaging an eccentric 26 mounted on the arm 18. The eccentric 26 is secured to the arm 18 by a screw 28 which can be loosened whereupon the eccentric can be rotated by a screw driver thrust into a slot 30. This provides a factory adjustment for the arm 18 relative to the arm 20.

The arm 20 has an operating knob 32 which extends through a slot 34 of a grid-like casing member 36. The casing member 36 is held in position on the base 10 by spring catches 38.

I provide a hygroscopic control member A. It comprises a corrugated element 40 of resilient material, such as sheet metal, a humidity responsive element 42 which will expand or swell upon an increase of humidity in the surrounding atmosphere and a switch arm 44.

The element 42 may be made of paper or the like.

The element 42 has its ends secured by screws 46 and 48 to the arm 18 and to the switch arm 44, respectively. The switch arm includes a connecting member 44a of insulating material to prevent a short circuit between the switch arm 44 and the corrugated element 40.

It is desirable that the screws 46 and 48 make good connection with the ends of the paper element 42. I therefore provide metal clips 50 (see Figure 7) which are of triple thickness folded construction with the ends of the paper element 42 folded in them. Their shape is simplified in Figure 1 because the figure is on too small a scale to illustrate them in full detail.

The screw 46 anchors both one end of the element 42 and one end of the element 40 to the arm 18, which serves as an adjustable anchorage for the control member A. The screw 48 is provided for some longitudinal adjustment of the outer end of the paper element 42 relative to the corrugated element 40, such adjustment being effected at the factory. It will be remembered that the eccentric 26 is also a factory adjustment and after the screw 48 and the eccentric 26 are adjusted, the adjustment by the user can be effected by moving the knob 32 so as to adjust the hy-

grosopic control switch for desired operation, for instance slightly above or slightly below a forty-five per cent humidity condition.

The switch arm 44 carries a movable contact 52 adapted to coat with an intermediate spring mounted contact 54, which in turn coacts with a stationary contact 56 for establishing an electric circuit.

The circuit may extend through a humidifying device or the like for increasing the humidity content of the atmosphere when the switch contacts are engaged. A permanent magnet 58 is provided to affect an armature piece 60 mounted on the switch arm 44 for providing snap action 25 when the switch contacts are separated.

In Figures 5 and 6, I have shown how the elements 40 and 42 can be somewhat simplified. In these figures, they are arranged in a straight line rather than spirally. The action of the control member is best illustrated in these figures.

In Figure 5, the action of the corrugated member 40 because of excessive dryness in the atmosphere is illustrated by dotted lines. The contacts 52 and 56 have been engaged because of the 25 contraction of the paper element 42, but thereafter a continued dry condition of the air has caused further contraction. Such further contraction, instead of placing the paper element 42 under greatly increased strain, merely causes 30 the corrugations to be contracted, for instance to the dotted line position (which is greatly exaggerated). Thus an overrun in the dry direction is effectively taken care of.

In Figure 6, an overrun in the humid direction is illustrated. A stop is shown diagrammatically at 61, which in the case of the device shown in Figures 1 and 2, would be the casing 36. An increase in humidity after the control member strikes the stop would tend to lengthen the paper element 42, for instance, to the dotted line position and it could merely buckle away from the corrugated element 40 without placing any undesired strain on the parts.

The sensitivity of the hygroscopic control member may be predetermined by the thickness of the material in the element 40 and the depth of the corrugations. For instance, in Figure 5, thin material and deep corrugations are illustrated which would provide a much more sensitive control device than the one shown in Figure 6 wherein the material is thicker and the corrugations are shallower. The difference in Figures 5 and 6 illustrates how various adaptations of the invention can be worked out, the element in Figure 5 being considerably more powerful than the one in Figure 5. Thus the construction can be varied to make the invention applicable to different installations.

In Figure 4, I have shown by dotted lines how 60 the paper element 42 can buckle away from the corrugated element 40 when the parts of a spirally arranged hygroscopic control member are in the position illustrated by Figure 6.

My hygroscopic member is so constructed as to 65 prevent strains caused by over and under runs which would be encountered in members composed of elements cemented or otherwise secured together.

A further advantage resides in the spaces between the apices of the corrugations of the element 40 providing extra surface for contact of the atmosphere with the humidity responsive element 42.

Changes as already suggested and others may 75 be made without departing from the real spirit

and purpose of my invention, and it is my intention to cover by my claims, any modified forms of structure or use of mechanical equivalents, which may be reasonably included within their scope.

I claim as my invention:

1. In a hygroscopic control device, a control member comprising a corrugated metal element and a humidity responsive element arranged side by side, the ends of said humidity responsive element being secured to the ends of said corrugated metal element, one end of said control member being anchored whereby the other end thereof moves laterally dependent upon humidity conditions of the surrounding atmosphere. 90

2. In a hygroscopic control device, a control member comprising a corrugated resilient element and a humidity responsive element arranged side by side, the ends of said humidity responsive element being secured to the ends of said corrugated resilient element, one end of said control member being anchored whereby the other end thereof moves laterally dependent upon humidity conditions of the surrounding atmosphere. 95

3. In a hygroscopic control device, a control member comprising a corrugated resilient element and a humidity responsive element arranged side by side, the ends of said humidity responsive element being secured to the ends of said corrugated resilient element and anchorage means, one end of said control member being secured thereto whereby the other end of said member will move laterally depending upon the moisture content of the surrounding atmosphere. 100

4. In a hygroscopic control device, a control member comprising a corrugated resilient element and a humidity responsive element arranged side by side, the ends of said humidity responsive element being secured to the ends of said corrugated resilient element, anchorage means, one end of said control member being secured thereto whereby the other end of said member will move laterally depending upon the moisture content of the surrounding atmosphere and 110 adjustable means for changing the position of said anchorage means and thereby the position of said other end of said control member and the setting of said control device.

5. In a hygroscopic control device, a control member comprising a corrugated element and a humidity responsive element arranged side by side, the ends of said humidity responsive element being secured to the ends of said corrugated element but being otherwise free therefrom, one end 120 of said control member being anchored whereby the other end thereof moves laterally dependent upon humidity conditions of the surrounding atmosphere. 125

6. A humidity sensitive element comprising a curved spring, a thin flexible hygroscopic strip and means for supporting said strip thereon in spaced relation to spaced portions of the convex face of said curved spring, said means providing aeration for the inner surface of said hygroscopic strip, the ends of said strip being secured to the ends of said curved spring, one end of said humidity sensitive element being anchored and the other end providing lateral movement with a change of humidity of the surrounding atmosphere. 140

7. An elongated humidity sensitive element comprising a curved spring, a hygroscopic strip and means for supporting said strip in spaced relation to spaced portions of the convex face of 145

said curved spring, the ends of said hygroscopic strip being secured to the ends of said curved spring, one end of said humidity sensitive element being anchored, the other end thereof providing lateral movement with a change of humidity of the surrounding atmosphere, said curved spring being longitudinally flexible to limit the stress in said hygroscopic strip at low humidity.

10. 8. An elongated humidity sensitive element comprising a flexible strip in curved form, formations on said strip and a hygroscopic strip held in spaced relation to spaced portions of the outer face of said flexible strip by said formations, the ends of said hygroscopic strip being secured to the ends of said flexible strip, one end of said humidity sensitive element being anchored, the other end thereof providing lateral movement with a change of humidity of the surrounding atmosphere, said flexible strip having limited longitudinal expansion for relieving the stress in said hygroscopic strip at high humidities.

25. 9. In a humidity sensitive element, a curved spring having spaced projections on the convex side thereof and a thin flexible hygroscopic strip having its ends only anchored to the ends of said curved spring and lying along said projections, one end of said element being anchored whereby the other end moves laterally in response to humidity changes of the surrounding atmosphere.

30. 10. In a humidity sensitive element, a spirally arranged spring having spaced projections on the

convex side thereof and a thin flexible hygroscopic strip having its ends anchored to said spring and lying along said projections, the space between said projections providing air spaces for aeration of the hygroscopic strip, one end of said element being anchored whereby the other end thereof moves laterally in response to humidity changes of the surrounding atmosphere.

11. In a humidity sensitive element, a curved flexible element having spaced projections on the convex side thereof and a thin flexible hygroscopic strip anchored to said curved flexible element and lying along and tangent to the outer end of each of said projections, one end of said humidity sensitive element being anchored whereby the other end moves laterally in response to humidity changes of the surrounding atmosphere.

12. A humidity sensitive element comprising a curved spring with integral projections on its convex surface and a strip of thin flexible hygroscopic material supported on the outer ends of said integral projections, the ends of said hygroscopic strip being secured to the ends only of said curved spring and thereby normally held in contact therewith, one end of said humidity sensitive element being anchored and the other end thereby providing lateral movement with a change of humidity of the surrounding atmosphere.
